ATTORNEY

UNITED STATES PATENT OFFICE.

CHARLES A. ALDEN, OF STEELTON, PENNSYLVANIA.

GUARD-RAIL CLAMP.

949,253.

Specification of Letters Patent. Patented Feb. 15, 1910.

Application filed April 1, 1909. Serial No. 487,150.

To all whom it may concern:

Be it known that I, CHARLES A. ALDEN, citizen of the United States, residing at Steelton, in the county of Dauphin and State 5 of Pennsylvania, have invented certain new and useful Improvements in Guard - Rail Clamps, of which the following is a specification.

This invention relates to guard rail 10 clamps, my object being to provide a simple, durable and efficient clamping device by means of which a railroad guard rail may be held in proper relation to a railroad main rail, and having provision whereby the 15 guard rail may be adjusted toward the main rail to compensate for wear.

With this object in view, the invention consists in the novel construction and combinations of parts which will be hereinafter 20 fully described and claimed.

In the drawings:—Figure 1 is a plan view of a portion of a railroad main rail and a railroad guard rail adjacent thereto, the guard rail being held in place by my improved clamping device. Fig. 2 is a vertical section on the line 2—2 of Fig. 1, including a portion of an underlying cross-tie supporting the rails. Fig. 3 is a perspective view of the spacing member of the clamp 30 and the removable shims in separated relation to each other.

3 designates a portion of a cross-tie upon which is supported the main rail 4 and the adjacent guard rail 5. The main rail comprises a base 6, a web 7, and a head 8, the same being of usual and well known construction. The guard rail comprises a base 9, a web 10, and a head 11. The web 10 of the guard rail 5 is inclined upwardly from 40 the base 9 of the guard rail toward the head 8 of the main rail to bring the head 11 of the guard rail into proper relation with the head 8 of the main rail, and to permit the base 9 of the guard rail to be adjusted to 45 ward the base 6 of the main rail to compensate for wear.

Arranged between the webs 7 and 10 of the main and guard rails 4 and 5 respectively, is a spacing member 12 provided with 50 a flange 13 extending therefrom parallel to the web 11 of the main rail and a flange 14 extending from the member 12 parallel to the web 10 of the guard rail. The flange 13 is in engagement with the web 7 of the main 55 rail and interposed between the flange 14

and the web 10 of the guard rail are removable shims 15.

Extending through the webs 7 and 10 of the rails, the flanges 13 and 14 of the spacing member 12, and the shims 15, is a securing 60 bolt 16 provided with an integral head 17 and an adjustable nut 18, by means of which the parts may be drawn together and secured in place. Each shim 15 is bifurcated as at 22 to permit it to embrace the securing 65 bolt 16, the width of the bifurcation of each shim 15 being substantially equal to the diameter of the bolt 16. It will thus be seen that by loosening the nut 18, one or both of the shims 15 may be removed from 70 the clamp without removing the bolt.

The flange 14 of the spacing member 12 is provided with an indentation 19, and the shims 15 are provided with indentations 20 and projections 21; and the indentations 19 75 and 20 and projections 21 are arranged in line with each other as shown, the projection 21 of the shim 15 next adjacent the flange 14 extending into the indentation 19 in the flange, and the projection 21 of the shim 15 80 next adjacent the web 10 of the guard rail extending into the indentation in the adjacent shim. It will thus be seen that the projections 21 engaging the indentations will prevent the withdrawal of the shims 20 from 85 the bolt 16 and will also prevent the turning of the shims about the axis of the bolt.

When the parts have been assembled as shown in Figs. 1 and 2, and the nut 18 tightened upon the bolt 16, the parts of the 90 clamp are securely held in position relatively to each other, and the guard rail 5 is securely held in proper relation to the main rail 4. When the head 11 of the guard rail becomes worn, thereby increasing the space 95 between the head of the guard rail and the head of the main rail, the guard rail may be adjusted toward the main rail to compensate for such wear by loosening the nut 18 and removing one of the shims 15, whereupon the nut 18 may be again tightened to 100 hold the parts in place.

I claim:—

1. The combination with the main rail having a base, a web and a head; and the 105 guard rail having a base, a web and a head; of a spacing member comprising a flat substantially vertically-arranged body portion extending transversely between said rails, a flange extending from the body portion 110

parallel to the web of the main rail and a flange extending from the body portion parallel to the web of the guard rail; and a bolt extending through said webs and said 5 flanges and securing the parts together.

2. The combination with the main rail having a base, a web and a head; and the guard rail having a base, a web and a head; of a spacing member comprising a flat substantially vertically-arranged body portion 10 extending transversely between said rails and having its lower edge engaging the base of the main rail, a flange extending from the body portion parallel to the web of the main rail and a flange extending from the body portion parallel to the web of the 15 guard rail; and a bolt extending through said webs and said flanges and securing the parts together.

3. The combination of the main rail having a base, a web and a head, the guard rail having a base, a web and a head, a spacing member having an indentation therein and arranged between said webs, a shim inter- 20 posed between said member and one of said webs and having a projection extending into said indentation, and a securing bolt 25 extending through said webs and said member and said shim.

4. The combination of the main rail having a base, a web and a head, the guard rail having a base, a web and a head, a spacing member having an indentation therein and arranged between said webs, a securing bolt 30 extending through said webs and said member, and a bifurcated shim embracing said bolt between said member and one of said webs and having a projection extending into 35 said indentation.

5. The combination of the main rail having a base, a web and a head, the guard rail having a base, a web and a head, a spacing member having a flange extending parallel 40 to the web of the main rail and a flange ex-

tending parallel to the web of the guard 45 rail, one of said flanges having an indentation therein, a securing bolt extending through said webs and said flanges, and a bifurcated shim embracing said bolt between the flange provided with the indentation and one of said webs, said shim having a projection extending into said indentation.

6. The combination of the main rail having a base, a web and a head, the guard rail having a base, a web and a head, a spacing 50 member having a flange extending parallel to the web of the main rail and a flange extending parallel to the web of the guard rail, one of said flanges having an indentation therein, a plurality of shims interposed 55 between the flange provided with the indentation and one of said webs, said shims having indentations and projections in line with each other and with the indentation in one of said flanges, and a securing bolt extending 60 through said webs and said flanges and said shims.

7. The combination of the main rail having a base, a web and a head, the guard rail having a base, a web and a head, a spacing 70 member having a flange extending parallel to the web of the main rail and a flange extending parallel to the web of the guard rail, one of said flanges having an indentation therein, a securing bolt extending 75 through said webs and said flanges, and a plurality of bifurcated shims embracing said bolt between the flange provided with the indentation and one of said webs, said shims having indentations and projections 80 in line with each other and with the indentation in one of said flanges.

In testimony whereof I affix my signature in presence of two witnesses.

CHARLES A. ALDEN.
